JOHN N. WEIMER, OF INDIANAPOLIS, INDIANA.

MACHINE FOR BENDING LEATHER EDGEWISE.

1,255,366.

Specification of Letters Patent.

Patented Feb. 5, 1918.

Application filed October 23, 1916. Serial No. 127,086.

To all whom it may concern:

Be it known that I, JOHN N. WEIMER, a citizen of the United States, residing at Indianapolis, in the county of Marion and 5 State of Indiana, have invented a new and useful Machine for Bending Leather Edge-wise, of which the following is a specification.

It is the object of my invention to bend 10 leather strips edgewise, so as to form the leather facings for cone clutches.

In carrying out my invention, I provide 15 two feed rollers for feeding the leather strip forward, and guides on the intake and discharge sides of said rollers for acting against the edge of the leather strip, the guide on the discharge side being displaced toward the leather strip from the plane perpendicular to the roller axes and containing the 20 other guide; and I preferably provide members coöperating with the faces of the leather strip to prevent it from buckling as it is being bent edgewise. Preferably, I employ my invention in connection with a standard 25 leather-splitting machine, which has the rollers and the guide on the intake side of the rollers, and a knife for splitting the leather to obtain the desired thickness, as thereby I am able to obtain both the splitting 30 and the bending in one operation.

The accompanying drawing illustrates my invention. Figure 1 is a plan view of a leather-splitting machine equipped with my device for producing edgewise bending of 35 the leather, showing the machine somewhat diagrammatically; Fig. 2 is a side elevation of such machine, partly in section; Fig. 3 is a partial plan view showing the adjustability of the bending guide; Fig. 4 is a 40 perspective view of the bending guide; Fig. 5 is a plan view, on a smaller scale, of a leather strip after it has been bent edge-wise; and Fig. 6 is a sectional view of such a bent strip after it has been formed into 45 the truncated cone shape required for the facing of a clutch cone.

The two feed rollers 10 and 11 are driven in any suitable manner in the direction of the arrows to feed in the direction of the 50 arrow over the feed table 12 and discharge table 13 the leather strip 14 to be split and bent edgewise. At the receiving end of the discharge table 13 and projecting well into the space between the rollers 10 and 11 is 55 the splitting knife 15, which splits the leather strip 14 into the upper part 16 to

be bent and the lower part 17 which is discharged downward for possible other use.

The discharge table 13 usually slants upward from the splitting knife 15 for a distance, and then extends horizontally, as clear from Fig. 2. An intake guide 18 bears against one edge of the leather strip 14—the edge which is to be convex—on the 60 intake side of the rollers 10 and 11. A bending guide 20 bears against the same edge of the upper portion 16 of the strip 14 on the discharge side of the rollers 10 and 11, but at a point which is displaced 65 toward the leather strip from that plane perpendicular to the axes of the rollers 10 and 11 in which the intake guide 18 lies. The bending guide 20 is preferably adjustable about a pivot 21, so as to vary the 70 amount of bending given the leather strip 16. When my invention is applied to existing splitting machines, this pivot 21 is preferably provided between the bending 75 guide 20 and an overlying plate 22, which 80 bears against any suitable attaching points on the splitting machine, as against lugs 23 on the discharge table 13, and is clamped in such position by a bolt 24 which extends through such plate 22 and the discharge 85 table 13 and also through an arc-shaped slot 25 in the bending guide 20 so that it serves not only to clamp the parts in place but to lock the bending guide in the desired 90 angular position. The upper portion 16 of 95 the leather strip to be bent edgewise travels between the overlying plate 22 and the table 13, at the point where it is acted on by the bending guide 20, and is thereby prevented from buckling during the edgewise bending operation.

In operation, the leather strip 14 is fed in the direction of the arrow between the rollers 10 and 11, with one edge of the strip bearing against the intake guide 18. 100 As the strip 14 passes between the rollers 10 and 11, it strikes the splitting knife 15, and is split into the upper and lower strips 16 and 17. The upper section 16 passes on to the table 13, and strikes the bending 105 guide 20, which forces it out of the line in which it is being fed between the rollers 10 and 11 to bend it edgewise in the direction shown, the overlying plate 22 and the underlying table 13 coöperating to prevent 110 the strip 16 from buckling as it is being bent. The operation of the rollers 10 and

11 forces the leather strip 14 against the knife 15, and also exerts a force on the leather strip tending to force that part of it which is between the guides 18 and 20 out of the straight line joining such guides, thus creating opposing forces, by the guides 18 and 20 in one direction and the rollers 10 and 11 at an intermediate point in the other direction, tending to produce the edge-wise bending of the strip as it is fed between the rollers. Different degrees of bending may be obtained by adjusting the discharge guide 20 about its pivot 21. The finished strip, shown in Fig. 4, is permanently bent 15 edgewise, as indicated, so that it can be rolled into the form of a truncated cone, as shown in Fig. 5, to form a facing for a clutch cone.

If desired, especially where the table 13 first slants upward from the discharge side 20 of the rollers and then extends horizontally, so that the space between the table 13 and the overlying plate 22 is wedge-shaped, the bending guide 20 may be provided with a 25 laterally projecting wedge-shaped tongue 26 which extends under the bent leather strip and confines it within a parallel-sided space provided by such tongue and the overlying plate 22. This assists in preventing buckling 30 of the leather strip, and is especially desirable when the more flexible leather is being operated upon.

I claim as my invention:

1. A combined splitting and edgewise bending machine for leather, comprising a pair of feed rollers having parallel axes for feeding the leather strip between them, a splitting knife for splitting the leather as it is discharged from said rollers, an intake 35 guide bearing against the edge of the leather strip on the intake side of the rollers, and a bending guide bearing against the same edge of one of the parts of said leather strip on the discharge side of the rollers after the 40 splitting has occurred, said bending guide being displaced toward the leather strip from that plane perpendicular to the axes of the rollers which contains the intake 45 guide.
2. A combined splitting and edgewise bending machine for leather, comprising a pair of feed rollers having parallel axes for feeding the leather strip between them, a splitting knife for splitting the leather as it 50 is discharged from said rollers, an intake 55 guide bearing against the edge of the leather strip on the intake side of the rollers, a bending guide bearing against the same edge of one of the parts of said leather strip on the discharge side of the rollers after the splitting has occurred, said bending guide being displaced toward the leather strip from that plane perpendicular to the axes of the rollers which contains the intake guide, and members coöperating with the two faces of the leather strip at the bending guide to prevent buckling of the leather as it is operated on by said bending guide.

guide bearing against the edge of the leather strip on the intake side of the rollers, a bending guide bearing against the same edge of one of the parts of said leather strip on the discharge side of the rollers after the 60 splitting has occurred, said bending guide being displaced toward the leather strip from that plane perpendicular to the axes of the rollers which contains the intake guide, and means for permitting the varying of the relative positions of said two guides axially of the rollers.

3. A combined splitting and edgewise bending machine for leather, comprising a pair of feed rollers having parallel axes 70 for feeding the leather strip between them, a splitting knife for splitting the leather as it is discharged from said rollers, an intake guide bearing against the edge of the leather strip on the intake side of the rollers, and 75 a bending guide bearing against the same edge of one of the parts of said leather strip on the discharge side of the rollers after the splitting has occurred, said bending guide being displaced toward the leather 80 strip from that plane perpendicular to the axes of the rollers which contains the intake guide, said bending guide being pivotally mounted so that it can be adjusted to different positions relative to the aforesaid plane. 85

4. A combined splitting and edgewise bending machine for leather, comprising a pair of feed rollers having parallel axes for feeding the leather strip between them, a splitting knife for splitting the leather as it 90 is discharged from said rollers, an intake guide bearing against the edge of the leather strip on the intake side of the rollers, a bending guide bearing against the same edge of one of the parts of said leather strip on the 95 discharge side of the rollers after splitting has occurred, said bending guide being displaced toward the leather strip from that plane perpendicular to the axes of the rollers which contains the intake guide, and members coöperating with the two faces of the leather strip at the bending guide to prevent buckling of the leather as it is operated on by said bending guide.

In witness whereof, I have hereunto 105 set my hand at Indianapolis, Indiana, this 21st day of October, A. D. one thousand nine hundred and sixteen.

JOHN N. WEIMER.
